UNITED STATES PATENT OFFICE.

THOMAS E. BARNUM, OF MILWAUKEE, WISCONSIN, ASSIGNOR TO THE CUTLER-HAMMER MFG. CO., OF MILWAUKEE, WISCONSIN, A CORPORATION OF WISCONSIN.

MOTOR-CONTROLLER.

1,079,386.

Specification of Letters Patent.

Patented Nov. 25, 1913.

Application filed May 13, 1909. Serial No. 495,738.

To all whom it may concern:

Be it known that I, THOMAS E. BARNUM, a citizen of the United States, residing at Milwaukee, in the county of Milwaukee and 5 State of Wisconsin, have invented new and useful Improvements in Motor-Controllers, of which the following is a full, clear, concise, and exact description, reference being had to the accompanying drawing, forming 10 a part of this specification.

My invention relates to improvements in controllers for electric motors, and more particularly to adjustable speed regulators.

The various objects and advantages of my 15 invention will be hereinafter clearly and fully set forth.

In order to fully disclose the characteristic features of my invention, I shall describe the device illustrated in the accompanying 20 drawing, which embodies my invention in its preferred form. Of course, my invention is susceptible of various modifications.

In the accompanying drawing, Figure 1 is a front elevation of a device, a portion 25 thereof being shown in section. This figure also illustrates diagrammatically one circuit arrangement for the device. Fig. 2 is a sectional view taken through a portion of the device.

30 The several parts of the device are preferably mounted upon an insulating panel or base 1. Fulcrumed on a pin or stud 2 projecting from the base 1 is an arm 3. At its outer end, the arm 3 carries contact brushes 4 and 5. As the arm 3 is moved, the brush 4 is adapted to pass over a series of contacts 6 and a contact segment 7, while the brush 5 is adapted to pass over a contact segment 8 to a series of contacts 9.

40 Downward movement of the arm 3 is limited by stop 10 mounted on the base 1. The arm 3 is adapted to be actuated by a rocker arm 11, which is also fulcrumed on the pin or stud 2. The rocker arm 11 is prefer- 45 ably provided with a lateral extension 12, provided at its extremity with a hollow cylindrical portion 13. (See Fig. 2.) Ex- 50 tending longitudinally through the cylindrical portion 13 is a pin 14, provided with a head 15, adapted to bear against the top of the portion 13. Suitably secured to the pin 14, within the cylindrical portion 13, is a collar 16, which cooperates with the inner 55 wall of the portion 13 to guide the pin 14. Surrounding the pin 14 and interposed be-

and the collar 16 is a coil spring 17, which tends to hold the pin 14 in the position illustrated in Fig. 2. The pin 14 serves as a means for connecting the rocker arm 11 60 to the controlling arm 3 in the following manner. The arm 3 is provided with an enlarged portion 18, in which is provided a series of apertures 19. The pin 14 is arranged to fit into any of the apertures 19 65 in the arm 3, and in this way connects the arm 3 to the rocker arm 11. The purpose of this arrangement will be hereinafter set forth.

The rocker arm 11 is adapted to be actuated by a solenoid 20, mounted in a suitable frame 21, secured to the base 1 by any suitable means such as bolts 22. The solenoid 20 is provided with a movable plunger 23, which is connected by link 24 to the 70 rocker arm 11. Hence, when the solenoid 20 is energized, it draws in its plunger 23, thereby raising the rocker arm 11. The rocker arm 11, in turn, raises the controlling arm 3. The rocker arm 11 is prefer- 75 ably provided with an extension 25, which carries at its extremity an upwardly extending pin 26. The pin 26 preferably comprises a screw which may be suitably adjusted. Arranged in the path of the pin 26 is a 80 switch 27. The switch 27 preferably com- 85 prises a strip of spring metal rigidly secured at one end to a suitable support 28 carried by the panel 1 and adapted at its other end to engage a suitable contact 29 90 also secured to the base 1. When the rocker arm 11 reaches the limit of its movement, the pin 26 carried thereby engages the switch 27, thereby opening the same and maintaining the same open until the rocker 95 arm 11 descends.

For retarding the upward movement of the rocker arm 11 and the arm 3, I prefer- 100 ably provide a dash pot 30. The dash pot is preferably pivoted to a support 31 se- 105 cured to the base 1. In practice, the dash pot may assume any preferred form, but I prefer to use an oil dash pot having the characteristics which will be hereinafter set forth. The dash pot illustrated is provided with a plunger 32, which is connected by a 110 rod 33 to an extension of the rocker arm 11. In order to permit freedom of move- 115 ment of the plunger 32 in an upward direction, the same may be provided with apertures 34, adapted to be closed by valve 35 when the plunger descends. At the

lower end of the dash pot are provided two series of apertures 36 and 37, which communicate with an enlarged outer chamber 38. With this arrangement, as the rocker arm 11 is moved upwardly, the plunger in the dash pot is forced downwardly, and, when moved in this direction, retards the movement of the rocker arm 11. As the plunger 32 passes the apertures 36 at the lower end of the dash pot, the fluid beneath the plunger is forced through the apertures 37 into the chamber 38, and thence back through the apertures 36. This practically eliminates all opposition to the downward movement of the plunger of the dash pot, and consequently allows the rocker arm 11 to be moved freely at the end of its travel. This, together with the fact that the magnetic pull upon the plunger of the solenoid 20 becomes very great as the plunger nears the limit of its travel, the rocker arm is moved very rapidly as it reaches the limit of its travel. This causes the pin carried by the rocker arm 11 to impart more or less of a quick blow to the switch 27, thereby opening the same very quickly. The rocker arm 11 is always drawn to the limit of its movement when its operating solenoid is energized, and, consequently, the plunger of the dash pot will always complete its stroke, thereby always insuring a quick opening of the switch 27.

The circuit diagram which I have shown is very simple and serves merely to disclose the functions of the device. The motor illustrated is of the shunt wound type, being provided with an armature A and a shunt field winding F. Of course, a compound motor could be used instead of a shunt wound motor. One terminal of the motor armature is connected by conductor 40 through a double pole switch 41 to one side of the supply circuit. The opposite terminal of the motor armature is connected by conductors 42 and 43 to contact segment 7. Contact segment 7 is connected to the first adjacent contact of the series of contacts 6. All of the series of contacts 6 are connected to an armature resistance 44. One terminal of the shunt field winding of the motor is connected to conductor 40, while its opposite terminal is connected by conductor 45 to contact segment 8. Contact segment 8 is connected to the first adjacent contact of the series of contacts 9. The contacts 9 are all connected to a field regulating resistance 46. The arm 3 is connected by conductors 47 and 48 through the switch 41 to the opposite side of the main line. One terminal of the solenoid winding 20 is connected by conductor 49 to conductor 40, while its opposite terminal is connected by conductor 50 through switch 27 by conductor 51 to conductor 47. The switch 27, when closed, shortcircuits a resistance 52.

I shall now describe the operation of the controller. Upon closure of the switch 41, circuit is closed through the motor. The armature circuit may be traced from conductor 40 through the armature, by conductors 42 and 43 to contact segment 7, thence through all of the resistance 44 to the arm 3, and through said arm by conductors 47 and 48 to the opposite side of the supply circuit. The field circuit of the motor may be traced from conductor 40 through the field winding by conductor 45 to contact segment 8, thence directly through the arm 3 and by conductors 47 and 48 to the opposite side of the supply circuit. The motor is thus started with all of the resistance 44 in its armature circuit and with no resistance in its field circuit. Upon closure of the motor circuit, circuit is also closed from conductor 40 by conductor 49, through the solenoid winding 20, through switch 27, by conductor 51 to conductor 47. This causes the energization of the winding 20 which immediately draws up its plunger, thereby operating the rocker arm 11 against the action of the dash pot 30. The rocker arm 11 in turn gradually moves the arm 3 upwardly, thereby gradually removing the armature resistance from circuit and increasing the speed of the motor. After the arm 3 has been sufficiently raised to remove all of the armature resistance from circuit, the brush 5 carried thereby passes from the segment 8 onto the contacts 9. Further movement of the arm 3 gradually inserts the resistance 46 in the field circuit of the motor, thereby gradually increasing the speed of the motor. The number of the contact 9 over which the brush 5 is thus moved depends upon the adjustment between the rocker arm 11 and the arm 3. Regardless of this adjustment, however, as the rocker arm 11 approaches the limit of its movement, the pin 26 carried thereby strikes the switch 27, thereby opening the same with a quick action. This results in inserting the resistance 52 in the circuit of the solenoid 20. The resistance 52 is so proportioned as to reduce the flow of current through the winding to an amount just sufficient to maintain the plunger 23 in final position. With the rocker arm and controlling arm connected as illustrated, the arm 3 would probably not pass over more than one or two of the field regulating contacts and, consequently, the motor would not attain its highest speed, but would operate at an intermediate speed. To vary the maximum speed at which it is desired to operate the motor, it is only necessary to withdraw the pin connecting the two arms and insert the same in another one of the apertures in the arm 3. To increase the maximum speed of the motor, the pin should be inserted in one of the lower apertures, and, to decrease

the maximum speed, the pin should be inserted in one of the upper apertures. Of course, the armature resistance might be designed merely for starting the motor and 5 not for regulating the speed thereof, and, in such an event, the speed of the motor should be varied by varying the field resistance.

Having thus described my invention, what I claim as new and desire to secure by Letters Patent, is:—

1. In a controller for electric motors, in combination, a movable controlling element, a pivoted operating member therefor, having a limited movement and an adjustable 15 connection between said member and said element for varying the limit of movement of said element.

2. In a controller for electric motors, in combination, a pivoted contact device, an operating member therefor, pivoted concentrically therewith, said operating member having a limited movement and an adjustable connection between said member and said element for varying the limit of movement 25 of said device.

3. In a controller for electric motors, in combination, a movable controlling member, a movable operating member therefor, having a limited movement, one of said members having a plurality of apertures therein, and the other of said members having a device arranged to fit into any of said apertures to adjustably connect said members to vary the limit of movement of said controlling member.

4. In a controller for electric motors, in combination, a pivoted contact member, a pivoted operating member therefor, having a limited movement, said members being pivoted concentrically, one of said members having a series of apertures therein, and the other of said members having a spring pressed device adapted to fit into different apertures to adjustably connect said members to vary the limit of movement of said contact member.

5. In a controller for electric motors, in combination, a pivoted controlling element, a plurality of resistance contacts arranged to be engaged thereby, an automatically operated rocker arm for actuating said element, said rocker having a limited movement, and an adjustable connection between said arm and said element for causing said 55 arm to stop said element in final position on different contacts.

6. In a controller for electric motors, in combination, a movable controlling element, an automatically operated rocker arm for operating said element, said arm having a limited movement, an adjustable connection between said arm and said element for varying the limit of movement of said element,

a switch adapted to be actuated by said arm upon reaching the limit of its movement, 65 and means for retarding the operation of said arm, said means being arranged to permit said arm to accelerate at the limit of its movement to quickly actuate said switch.

7. In a controller for electric motors, in combination, a movable controlling element, a pivoted member for actuating said element, a solenoid for moving said member to a predetermined limit, an adjustable connection between said member and said element 75 for varying the limit of movement of said element, a switch arranged to be operated by said member at the limit of its movement to reduce the flow of current through its operating solenoid, and means for retarding the 80 operation of said member, said means being arranged to permit said member to accelerate at the limit of its movement to quickly actuate said switch.

8. In a controller for electric motors, in combination, an armature resistance, a field resistance, a controlling element adapted to be actuated to gradually remove said armature resistance from circuit, and then gradually insert said field resistance in circuit, a 90 rocker arm for actuating said element, a solenoid for moving said arm to a predetermined limit, and an adjustable connection between said arm and said element, for causing said arm to bring said element to 95 rest in different predetermined positions to cause the motor to operate at different predetermined speeds.

9. In a controller for electric motors, in combination, an armature resistance, a field 100 resistance, a controlling element adapted to be actuated to gradually remove said armature resistance from circuit, and then gradually insert said field resistance in circuit, a 105 rocker arm for actuating said element, a solenoid for moving said arm to a predetermined limit, an adjustable connection between said arm and said element, for causing said arm to bring said element to rest in different predetermined positions to cause 110 the motor to operate at different predetermined speeds, a switch arranged to be actuated by said arm at the limit of its movement to reduce the flow of current through said solenoid, and a dash pot connected to said arm to retard the same, said dash pot being constructed to permit said arm to accelerate at the limit of its movement to quickly actuate said switch.

In witness whereof, I have hereunto subscribed my name in the presence of two witnesses.

THOMAS E. BARNUM.
